UNITED STATES PATENT OFFICE.

WILFRED J. DREY, OF CARLISLE, PENNSYLVANIA, ASSIGNEE, BY MESNE ASSIGNMENTS, TO UNITED SHOE MACHINERY CORPORATION, OF PATERSON, NEW JERSEY, A CORPORATION OF NEW JERSEY.

APPARATUS FOR COVERING THE HEELS OF SHOES.

1,341,737.

Specification of Letters Patent.

Patented June 1, 1920.

Application filed October 13, 1917. Serial No. 196,368.

To all whom it may concern:

Be it known that I, WILFRED J. DREY, a citizen of the United States, residing at Carlisle, in the county of Cumberland and 5 State of Pennsylvania, have invented certain Improvements in Apparatus for Covering the Heels of Shoes, of which the following description, in connection with the accompanying drawings, is a specification, 10 like reference characters on the drawings indicating like parts in the several figures.

My invention relates to apparatus for applying to shoe heels leather or other flexible covering material and especially concerns 15 means for performing this operation after the heel is in place upon the shoe.

Heretofore shoe heels have been covered satisfactorily only by hand and before attachment to the shoes, since manual methods 20 are not applicable to heels when in place. This makes necessary the use of a one-piece heel, usually of wood, because pieced heels constructed of lifts can only be trimmed effectively upon the shoes. These solid heels 25 are expensive and troublesome to securely and neatly attach, it being impossible to practice the well-known system of double nailing or to drive the fastenings from the outside. As covering heels by hand requires

30 considerable skill, it is often difficult for shoe manufacturers to keep in their employ the number of capable operators necessary to produce the required supply. For this reason it has been the common practice for 35 shoe manufacturers to cut out the heel coverings from suitable stock at the same time the upper leather is cut and send these to manufacturers of heels to do the covering and return the finished heels for application 40 to the shoes. This leads to obvious inconveniences and loss of time.

An object of this invention is to provide 45 an apparatus by the use of which an operator having little experience may cover all types of heels satisfactorily, both with respect to the quality of the work and speed of production. For this purpose my apparatus includes novel means for engaging the covering or its appendages to apply it to a 50 suitably supported heel under the control of the operator by a relative movement between the covering-engaging means and heel.

Another object of the invention is to furnish means whereby the covering may be

effectively applied to the ordinary heel of 55 leather, leather-board or the like, formed in lifts and attached to the shoe in the usual manner. To this end I employ means for forcing the covering into the space between the heel and upper. This may be accomplished in accordance with the method of 60 my Patent No. 1,208,760, patented Dec. 19, 1916, in which the covering is provided with attaching means, as a wire, located beneath a fold at the upper edge of the covering 65 and adapted to enter the space or rand crease between the heel and upper, and my improved apparatus has means to engage this wire and seat it securely within the crease, while other engaging means coöperate 70 with the covering to complete the operation. Preferably, though not necessarily, these engaging means are mounted to move together.

A further object of the invention is to insure 75 the uniform application of the covering to the heel without straining the covering stock, this being accomplished by rendering the engaging means at opposite sides of the heel independently movable, so that 80 the tension may be applied as the conditions of the covering and its relation to the heel demand.

One form of apparatus for attaining the 85 above objects and still others will now be described, reference being had to the accompanying drawings, in which,

Figure 1 is a perspective view of the apparatus looking at the forward portion;

Fig. 2 is a similar view taken from the 90 side;

Fig. 3 shows in plan the heel covering with its attaching member, as disclosed in my Patent No. 1,208,760;

Fig. 4 is a detail in perspective of a portion 95 of a shoe prepared for the attachment of the covering in accordance with the present invention;

Fig. 5 is a perspective view showing the entire heel and adjacent portions of the 100 shoe, with the elements of the machine engaged in the first step of the covering operation;

Fig. 6 is a similar view illustrating the 105 next step, and

Fig. 7 is a vertical sectional detail showing the relation of the covering attaching member to the rand crease.

Mounted upon a horizontal table 10 is a base portion 12, here shown as of cylindrical form, upon which is carried upon suitable ways a turn table 14 which may be so rotated that the elements thereon may be arranged to the best advantage for the operator. Rising from the center of the turn-table is a standard 16 for a work support. In the present instance, I have chosen to illustrate this as a jack 18 which may be of any desired type to hold a lasted shoe S, this being adapted for carrying out my preferred method of operation in which the covering is applied to the heel upon the shoe. Fixed to the top of the turn-table about the standard 16 is a supporting frame having a rectangular outer portion 20 and opposite arms 22 by which it is joined to the table. At opposite sides of the standard, spanning the rectangular portion of the frame, are transverse bars 24, 24. Pivoted at 26 upon the frame are supporting and actuating members for the covering-engaging and tensioning members to be later described, each of these actuating members consisting of a lever 28 the upper end of which extends by the jack to a point adjacent to the tread portion of the heel of the shoe which is supported on the jack. To permit the upper extremity of each lever to be adjusted to the correct relation, it is formed in sections of approximately equal length which are pivoted and clamped by a bolt 30. Upon each lever adjacent to the heel are located the covering-engaging members. When this covering C is provided with an attaching wire w, as described in my previously mentioned patent and particularly illustrated in Fig. 3 of these drawings, the lower member consists of a finger 32 pivoted at 34 on the lever 28 at a point somewhat below the heel seat of the shoe. At the opposite or free end of the finger is a groove 36, over which the wire w may be passed, and upon the inner side of the finger intermediate the groove 36 and the pivot 34 is a pin 38 or other securing means about which the wire may be twisted or by which it may be held to allow tension to be applied to it. Above the finger 32 toward the end of the lever 28 is another covering-engaging member, here shown as including an arm 40 pivoted upon the lever at 42 and having at its opposite end jaws or other covering-engaging means 44, these jaws preferably being normally held open by a spring 46. To clamp the jaws upon the covering a slide 48 surrounds them, which, when drawn back, forces the opposite members into engagement. The arm 40 extends from the opposite side of the lever from the finger 32 and is so curved that it may be moved from the idle position illustrated in Fig. 2 of the drawings over the top of the lever to the covering-engaging position shown in Fig. 1.

When located as first described, it leaves the finger 32 freely accessible to the operator. When the arm 40 is raised, the finger may be swung from its active position as it appears in Fig. 2 to that of Fig. 1, in which it is free from interference with the work or upper-engaging member.

To enable the members 28 to be simultaneously actuated to apply tension to both sides of the heel covering, there is mounted upon the bars 24 of the frame a slide having longitudinal bars 50, 50 and a forward connecting bar 52. This slide moves in ways in the bars 24, being retained in place by cap plates 54. At the end of the slide toward the operator, the cross bar 52 has an extension 58 to which is pivoted a hand lever 60 fulcrumed by means of a link 62 upon the frame 20. When the slide is moved by the lever 60, pins 63 projecting from the outer sides of the bars 50 contact in the forward movement of the slide with the rear edges of the levers 28, causing them to be swung away from the heel and to apply tension to a heel covering engaged by the members 32 and 44. In this adjusted position the slide may be retained by a detent 64 upon the lever 60, which detent engages one of a series of teeth 66 which I have shown as formed in a bar fixed to the side of the frame 20.

To allow the operator to apply tension selectively to either side of the heel covering, each of the levers 28 has at its outer side a headed projection 68 which may be engaged by one of a series of upwardly and rearwardly inclined depressions 70 in a link 72 pivoted at 74 upon a hand lever 76. Each of these levers 76 is fulcrumed at 78 upon one end of the forward cross bar 24. By causing one or another of the depressions 70 to engage the projection 68 the initial relation of the levers 28 and 76 to one another and to the work may be determined. When these elements are applying tension, they are retained in their forwardly adjusted positions by latch levers 80 pivoted upon the sides of the hand levers 76 and having rearwardly extending detent portions 82 for engagement with the teeth of segments 84. These segments or racks may be fixed to the upper faces of the opposite longitudinally extending bars of the frame 20. It will be seen that at any time in the operation of the apparatus, either of the levers 80 may be moved to actuate the corresponding lever 28 and thus enable the operator to apply greater tension to one side of the heel covering.

In using my improved apparatus, a shoe, as that shown at S, containing a last is mounted upon the jack 18, and the supporting frame turned by means of the table 14 into any position convenient for the operator and there clamped by a screw 86 or the like. This angular adjustment of the apparatus may be made at any time to give the operator easy

access to the work. The outside of the heel is coated with cement and the covering piece C, with its attaching wire w already in place thereon, is applied to the heel with its forward edges at equal distances beyond the heel breast. The ends of the wire are carried over the grooves 36 and twisted about the projections 38, the fingers 32 at this time being in the position illustrated in Fig. 2 and the levers 28 at such points that the ends of the fingers are just forward of the breast of the heel. Now with the wire opposite the rand crease, the slide 50 is drawn forward by the lever 60 until the wire is seated in the crease, this being facilitated, if necessary, by the use of a hand tool. Then the wire may be released from the projections 38, the fingers 32 swung back to the position of Fig. 1 and the ends of the wires, after preferably being passed through slots s cut in the edge of the sole at the junction of the shank and heel breast, twisted about tacks t driven into the breast of the heel just above the shank. The wire being thus secured, the tacks are driven into the heel and the forward edges of the covering folded over and cemented in place upon the heel breast, the covering at c being cut so that this may be readily and smoothly done. When the arms 40 are turned from the position of Fig. 2 to that of Fig. 1 the jaws 44 are brought opposite points in proximity to the tread surface of the heel and are then caused to engage the edges of the covering at these points. The operator thereupon gives the slide a further forward movement by the lever 60 to draw the covering in about the lower portion of the heel, at the same time working over the surface with a rubbing stick to insure firm contact and to smooth out wrinkles. If this results in an uneven application of the covering or if from imperfections in the stock or its coloring an uneven appearance develops, the operator may fix the slide by the detent 64 and apply tension to one side of the covering by actuating a hand lever 76. In this way the covering may be quickly and perfectly applied to the heel. At this stage the jaws 44 are released from the covering by sliding back the members 48 and the levers 20 may be swung entirely clear of the work. The outer edge of the covering is then brought over and cemented upon the tread surface of the heel, to which, by an operation independent of this apparatus, a toplift is applied, while the breast of the heel is finished in the usual manner by carrying the outsole over it.

Having thus described my invention, what I claim as new and desire to secure by Letters Patent of the United States is:

1. In an apparatus for covering heels attached to shoes, a shoe support, means for positively engaging the covering, and a support for the engaging means, one of said

supports being movable to apply the covering to the heel.

2. In an apparatus for covering heels attached to shoes, a shoe support, engaging means for the covering, a support for the engaging means, one of said supports being movable to apply the covering to the heel, and means for securing the support in the position to which it is moved.

3. In an apparatus for covering heels attached to shoes, a jack engaging means for drawing the covering into contact with the heel positioned with its shoe upon the jack, and a movable support for the engaging means.

4. In an apparatus for covering heels attached to shoes, a shoe support, engaging means for opposite sides of the covering, and a support for the engaging means, one of said supports being movable to draw the covering about the heel.

5. In an apparatus for covering heels, a heel support, engaging means for opposite sides of the covering, and means constructed and arranged to move the engaging means independently with respect to the heel.

6. In an apparatus for covering heels, a heel support, engaging means for opposite sides of the covering, and means constructed and arranged to move the engaging means independently with respect to the heel, the point of initial engagement between the moving means and the engaging means being variable.

7. In an apparatus for covering heels, a heel support, engaging means for opposite sides of the covering, means constructed and arranged to move the engaging means independently with respect to the heel, and means for locking each engaging means in the position to which it is moved.

8. In an apparatus for covering heels, a heel support, engaging means for opposite sides of the covering, and means constructed and arranged to move the engaging means simultaneously and independently with respect to the heel.

9. An apparatus for covering heels attached to shoes, comprising a heel support and means arranged to coöperate with the inner edges of the covering adjacent to the breast of a heel on the heel support for applying the covering to the heel preparatory to its permanent attachment to that heel.

10. In an apparatus for covering heels, a heel support, and independently movable means arranged to permit tension to be applied to the covering at opposite sides of the heel.

11. In an apparatus for covering heels, a heel support, and separate means arranged respectively for operation near the top and bottom of the heel to permit tension to be applied to the covering near such opposite extremities.

12. In an apparatus for covering heels, a heel support, and plural means arranged separately at each side of the heel to permit tension to be applied to the covering at opposite sides and near opposite extremities of said heel.
13. In an apparatus for covering heels, a plurality of tensioning members arranged for successive coöperation with the covering material to draw different portions about the heel.
14. In an apparatus for covering the heels of shoes, an applying member arranged to coöperate with the covering at the heel seat end of the heel, and an applying member thereafter coöperating with the covering at the opposite end of the heel.
15. In an apparatus for covering heels, a plurality of tensioning members arranged for successive coöperation with the covering material at each side of the heel to draw different portions about the heel.
16. In an apparatus for covering heels attached to shoes, a jack for the shoes, and means coöperating with the jack for forcing the covering material into the space between the heel and the upper.
17. In an apparatus for covering the heels of shoes, means for forcing the covering material into the space between the heel and the upper, and means operating thereafter for drawing other portions of the covering material about the heel.
18. In an apparatus for covering heels attached to shoes, a jack for the shoes, and means coöperating with the jack for inserting the edge of the covering material in the rand crease of a shoe to conceal said edge within the crease.
19. In an apparatus for covering the heels of shoes, movable means for drawing the covering material into the space between the heel and the upper, and means mounted to move therewith but having independent engagement with the covering for drawing other portions of said covering material about the heel.
20. In an apparatus for covering the heels of shoes with a covering provided with an attaching member, a shoe support and an engaging member for the attaching member, said engaging member being movable toward and from the shoe support.
21. In an apparatus for covering the heels of shoes with a covering provided with an attaching member, a shoe support, an engaging member for the attaching member, and an engaging member for the covering, said engaging members being movable toward and from the shoe support.
22. In an apparatus for covering the heels of shoes with a covering provided with an attaching member, a shoe support, an engaging member for the attaching member, and an engaging member for the covering,
- said engaging members being arranged in pairs at opposite sides of the shoe support and being movable toward and from said support.
23. In an apparatus for covering the heels of shoes with a covering provided with an attaching member, a shoe support, an engaging member for the attaching member, an engaging member for the covering, and an actuating member upon which the engaging members are mounted.
24. In an apparatus for covering the heels of shoes with a covering provided with an attaching member, a shoe support, an engaging member for the attaching member, an engaging member for the covering, and an actuating member upon which the engaging members are arranged to be moved into active and inactive positions.
25. In an apparatus for covering heels, a work support, actuating members movably mounted at opposite sides of the work support, and a plurality of engaging members for the covering carried by each actuating member.
26. In an apparatus for covering heels, a work support, actuating members movably mounted at opposite sides of the work support, members carried by the actuating members for positively engaging the covering, and means coöperating with the actuating members for moving them simultaneously.
27. In an apparatus for covering heels, a work support, actuating members movably mounted at opposite sides of the work support, engaging members for the covering carried by the actuating members, and means whereby the actuating members may be moved independently.
28. In an apparatus for covering heels, a work support, actuating members movably mounted at opposite sides of the work support, engaging members for the covering carried by the actuating members, means whereby the actuating members may be moved independently, and variable connections between the moving members and the actuating members.
29. In an apparatus for covering heels, a work support, actuating members movably mounted at opposite sides of the work support, engaging members for the covering carried by the actuating members, means for moving the actuating members simultaneously, and means whereby the actuating members may be moved independently.
30. In an apparatus for covering heels, a work support, actuating members movably mounted at opposite sides of the work support, and engaging members for the covering pivoted upon the actuating members for movement into and out of coöperation with the work.
31. In an apparatus for covering heels, a

work support, actuating members movably mounted at opposite sides of the work support and including relatively movable sections, and engaging members for the covering carried by the actuating members.

32. In an apparatus for covering heels, a work support, a lever fulcrumed at each side of the work support, an engaging member for the covering carried by each lever, and 10 a slide arranged to move both levers, said levers also being movable independently of the slide.

33. In an apparatus for covering heels, a work support, a lever fulcrumed at each 15 side of the work support, an engaging member for the covering movable by each lever, means for retaining each lever in the position to which it is moved, a slide coöperating with both levers, a lever for moving the 20 slide, and means for retaining the slide in the position to which it is moved by the lever.

34. In an apparatus for covering heels, a work support, a lever fulcrumed adjacent 25 to the work support, a member carried by the lever and arranged to apply tension to the covering by positive engagement therewith, an operating lever, and a link connect-

ing the operating lever and the lever carrying the engaging member.

35. In an apparatus for covering heels, a work support, a lever fulcrumed at each side of the work support, an engaging member for the covering carried by each lever, operating levers, and links connecting the operating levers and the levers carrying the engaging members, said links being provided with means for varying their points of attachment to the carrying levers.

36. In an apparatus for applying to the 40 heels of shoes a covering provided with an attaching member, a shoe support, a lever fulcrumed adjacent thereto, and covering-engaging jaws and an attaching-member-engaging finger carried by the lever.

37. In an apparatus for covering heels, a heel support and covering applying means provided with a pair of jaws at each side of the heel support and arranged to grip the inner edges of the covering adjacent to the 50 breast of the heel, said pairs of jaws being independently movable to tension the covering.

In testimony whereof I have signed my name to this specification.

WILFRED J. DREY.
